UNITED STATES PATENT OFFICE

2,538,565

AUTOMATIC STITCH LENGTH ADJUSTING MECHANISM

Carl W. Johnson, Brooklyn, N. Y., assignor to American Machine and Foundry Company, a corporation of New Jersey

Application August 11, 1942, Serial No. 454,353, now Patent No. 2,407,986, dated September 24, 1946, which is a division of application Serial No. 289,907, August 12, 1939, now Patent No. 2,368,066, dated January 23, 1945. Divided and this application October 20, 1945, Serial No. 623,567

6 Claims. (CL 112—210)

1

This invention relates to sewing machines and more particularly relates to improvements in mechanism for automatically controlling the length of stitches to be formed during the operation of the sewing machine on which it is employed.

This invention constitutes a division of co-pending application, Serial No. 454,353, filed August 11, 1942, for Stitch Length Adjusting Mechanism, now Patent No. 2,407,986, granted September 24, 1946, which is a division of application, Serial No. 289,907 filed August 12, 1939, now Patent No. 2,368,066 granted January 23, 1945.

This invention relates further to an adjunct for a sewing machine especially adaptable for use in connection with a sewing machine for making over and under type stitches of the general type shown in Johnson patent, No. 2,368,066 employing a double pointed needle having an eye located between the points thereof and has particular reference to mechanism for automatically controlling or varying the length of successive stitches being made so that material sewed has a pleasing and decorative appearance.

It is an object of my invention to provide improved mechanism for use with a sewing machine capable of automatically changing the stitch length so that successive stitches are of varying length.

It is also an object of my invention to provide automatic stitch length adjusting mechanism which controls the feed of work to be stitched past the needle in such a manner that successive stitches are of different lengths and a decorative and pleasing effect is obtained thereby.

With these and other objects not specifically mentioned in view, the invention consists in certain combinations and constructions which will be hereinafter fully described, and then specifically set forth in the claims hereunto appended.

In the accompanying drawings which form a part of this specification, and wherein the several reference characters designate the same or like elements:

Figure 1 is a side elevation showing the mechanism constituting the invention.

Figure 2 is an end view of Figure 1.

Figure 3 is a view of a detail.

Figure 4 is a view taken on line 4—4 of Figure 2.

2

Referring to the drawings, Figures 1 and 2 show a preferred form of the invention selected for purposes of illustration, which invention consists of an adjunct for a sewing machine such as a machine provided with opposed, vertically reciprocating needle bars (not shown) capable of projecting a needle and a thread having a loose end and a fixed end back and forth through the work in forming over and under type of stitches, or other type of sewing machine in which it is desired to automatically form successive stitches of different lengths.

Since the construction and operation of the needle projecting bars (not shown) and associated mechanisms form no part of the present invention, further showing and description thereof is omitted in the interest of brevity.

The work is fed over a table 13 of conventional design beneath a presser foot 15 provided to engage and retain it in sewing position. Presser foot 15 is mounted and operated in the manner disclosed in the above referred to patent, No. 2,368,066 so that it can be raised and lowered when desired to locate the work for proper feeding by feed bar 135. Feed bar 135 may be of the usual type employed in sewing machines and is arranged to project upwardly through a slot in table 13 over which the work is fed to and from the needle. As each stitch is completed arm 128 through its connections is caused to index. That is, arm 128 descends slightly below the level of table 13 leaving the work resting thereon, and the feed bar 135 mounted on arm 128 then moves up, engages and advances the work as the result of the movement of arm 128 in readiness for the next stitch, the work remaining in this position while arm 128 and feed bar 135 return to their original positions.

The right end of arm 128, as viewed in Figure 1, is mounted on a pivot stud 140 supported in lug 141 of an arm 142 loosely mounted on stud 134 which is suitably supported in a spacing block (not shown) secured to the frame of the machine 100. The other end of arm 128 (Figure 1) is pivotally connected to a link 127 which in turn is pivotally connected to the vertical arm of a bell crank lever 115 mounted on a pivot stud 116 fixed to the frame of the machine 100.

The general movement of arm 128 and feed

bar 135 is as follows: The general movement of arm 128 and feed

bar 135 attached thereto is in a closed uni-directional path. This movement can be separated into two main motions, i. e., an up and down or vertical motion, and a back and forth or horizontal motion. The up and down movement of arm 128 is imparted by a cam 110 with which coacts a cam follower 129 provided on an arm 130 of a bell crank lever loosely mounted on shaft 121a. The other arm 131 of the bell crank lever is connected to one end of an adjustable link 132 which in turn is connected to a depending portion 133 of arm 128. Cam follower 129 is maintained in tracking relationship with cam 110 by means of a spring 340 having one end attached to a pin 342 in member 121, and the other end attached to a pin 344 in frame 100. Cam 110 is mounted on a shaft 321 to which is fixed a sprocket 320 driven from a suitable sprocket and chain (not shown) from the main drive shaft of the sewing machine.

The back and forth or horizontal movement of arm 128 is effected by means of a crank pin 111 mounted on cam 110 provided with a roller 112 running in elongated slot 113 in the lower end of lever 114 fulcrumed to the horizontal arm of bell crank lever 115. A washer 112a on crank pin 111 maintains roller 112 in slot 113. Lever 114 is provided with a stud 118 carrying a follower 119 engaging a slot 120 in a slotted member 121 on shaft 121a. An arm 328, loosely mounted on shaft 121a, carries a cam follower 327 running on cam 326 and held in engagement therewith by means of a spring 346 having one end attached to a pin 343 secured to arm 328 and the other end attached to a suitable pin (not shown) in the frame 100.

The purpose of the slotted member 121 and arm 328 which is oscillated by cam 326 is to control the extent of vertical movement of lever 114 and the amount of horizontal movement of arm 128. In this way the length of each stitch made can be controlled. The amount of back and forth or horizontal movement of arm 128 and feed bar 135 supported thereon depends upon the position of slot 120 in member 121. By changing the angular relationship of slot 120 in subsequent stitching operations, the stitches made can be longer or shorter according to the setting of member 121. The more slot 120 is turned toward the vertical, the greater will be the feeding motion of feed bar 135 due to the fact that lever 114 pivoted upon lever 115 will be raised a greater amount; so also lever 115 will be rocked a proportionately greater amount. If it is desired to decrease the amplitude of feed bar 135, slotted member 121 will be so adjusted in the opposite direction so that the slot therein will be moved towards the horizontal. Since lever 115 is connected to link 127 connected to material feed arm 128, the resulting back and forth or horizontal motion imparted to arm 128 can be varied thereby making it possible to adjust the length and make longer or shorter stitches as required.

The mechanism for automatically producing alternate short and long stitches is constructed and operates as follows: A gear 322 fixed on shaft 321 meshes with and drives a gear 323 and its attached gear 324 loosely mounted on shaft 121a, while gear 324 in turn drives a gear 325 and a cam 326 loosely mounted on shaft 321. In this manner the gearing 322, 323, 324 and 325 drives cam 326 at one-half the speed of cam 110.

Lever 328 is adjustably attached to arm 329 clamped on shaft 121a by a thumb screw 330.

The lower portion of arm 329 is provided with an elongated slot 331 attached to engage thumb screw 330. By loosening the thumb screw 330, arm 329 may be moved relative to lever 328 and in so doing shift the position of slot 120 in slotted member 121 resulting in more or less movement of arm 128 and consequently longer or shorter stitches.

The cam 326 has a high portion 332 and a low portion 333, the surface 332 being considerably longer than 333 and therefore when it engages follower 327 it holds the slotted head of stitch control member 121 in a position to produce a long stitch. As the follower 327 rides off surface 332 and approaches surface 333, the slotted head of member 121 is turned to a position to produce a short stitch. The continuous rocking of the slotted head results in alternate long and short stitching of the work.

In the mechanisms hereinabove described it will be evident that I have provided means for forming stitches of a predetermined length and manually adjustable mechanism which provides for automatically varying successive feeding movements of the work feeding mechanism to form alternate long and short stitches in accordance with the wishes of the machine operator or the demands of a given piece of work being sewed or decorated.

The invention above described may be varied in construction within the scope of the claims, for the particular device, selected to illustrate the invention, is but one of many possible concrete embodiments of the same. It is not, therefore, to be restricted to the precise details of the structure shown and described.

What I claim is:

1. In a sewing machine, a work support, means for feeding work to be sewed along said support including a feed bar, and mechanism for varying the amount of movement of said means, said mechanism comprising a lever associated with said bar, a second lever pivoted on said first-named lever, means for oscillating said second lever, a follower carried by said second lever, a slotted member normally engaging said follower, and means for automatically shifting the position of said slotted member after the formation of each stitch to vary the extent of movement of said lever, said last-named means including a rotating cam and an element associated with said slotted member and coacting with said cam to alternately increase or decrease the amount of horizontal movement of said bar.

2. In a sewing machine, the combination with a work support, of mechanism for feeding work to be sewed along said support, means associated with said mechanism for adjusting the length of stitch to be made, said means including a slotted stitch length control member, means for adjusting the angular position of said slotted stitch length control member to make alternate long and short stitches, and cam operated means for moving said slotted stitch length control member after each stitch is formed to modify the movement of said feeding mechanism and thereby cause stitches of varying length to be formed.

3. In a sewing machine, work support, means for feeding work to be sewed along said support including a work feed bar, and mechanism for varying the amount of movement of said means, said mechanism comprising a lever associated with said bar, a second lever pivoted on said first-named lever, means for oscillating said second lever, a follower carried by said second lever, a

slotted member normally engaging said follower, means for shifting the position of said slotted member to vary the extent of movement of said lever, said last-named means including a cam, a shaft, an arm loose on said shaft, an adjusting arm fixed to said shaft, a cam follower on said loose arm tracking said cam, and adjusting means carried by said fixed arm for securing said arms together in predetermined position relative to said shaft and said loose arm to thereby adjust the length of alternate stitches formed.

4. In a sewing machine, means for feeding the work to form a predetermined normal length stitch, mechanism for changing the length of travel of said feeding means to change the length of stitch formed, said mechanism comprising a feed bar, means for imparting a normal closed path of movement to said bar, a stitch length control member, means for mounting said member for oscillatory movement, means for adjusting the angular position of said member to cause said bar to feed a predetermined normal length of work, and means for automatically turning said member after the formation of each stitch to cause said bar to feed a greater or lesser length of work and thereby vary the length of stitch formed.

5. In a sewing machine, means for feeding the work to form a predetermined normal length stitch, mechanism for changing the length of travel of said feeding means to change the length of stitch formed, said mechanism comprising a feed bar, means for imparting a normal closed path of movement to said bar, including means for imparting vertical motion to said bar, and means for imparting horizontal motion to said bar, an oscillatable stitch length control mem-

ber, means for mounting said member for oscillatory movement, means for adjusting the angular position of said member to cause said bar to feed a predetermined normal length of work, and means for automatically turning said member after the formation of each stitch to cause said bar to feed a greater or lesser length of work and thereby vary the length of stitch formed.

6. In a sewing machine, a work support, a traveling feed bar associated with said support, mechanism for imparting to said feed bar movement in a unidirectional closed path including an oscillatable slotted control member, a lever connected to said bar, a cam follower on said lever and tracking said slot in said member, means for adjusting the angular position of said member to determine the horizontal movement of said feed bar for producing normal stitches, means for maintaining said member in said adjusted position during operation of said machine, and selective means for moving said slotted member after the formation of each alternate stitch whereby the angular relationship of said slot and said follower is changed and the travel of said bar decreased to form shorter stitches.
